CLAIM

The ornamental design for a personal herb grinding device as shown and described.

DESCRIPTION

FIG. 1 is a top view of a personal herb grinding device showing my new design;

FIG. 2 is a bottom view thereof;

FIG. 3 is a left elevation view thereof;

FIG. 4 is a right elevation view thereof;

FIG. 5 is a front elevation view thereof;

FIG. 6 is a rear elevation view thereof;

FIG. 7 is a front-perspective view thereof; and,

FIG. 8 is a rear-perspective view thereof.

Any broken lines shown in the drawings represent portions of the personal herb grinding device that form no part of the claimed design.
